SAFETY ATTACHMENT FOR PRESSES

Joseph E. Skoog, Cranston, R. I.

Application April 21, 1944, Serial No. 532,135

4 Claims. (Cl. 74—615)

This invention relates to a safety attachment for a press which may be operated by either foot or power.

An operator of a press where small work is handled frequently fails to remove his fingers from beneath the plunger which descends upon the work, thereby causing injury to the operator. An attachment to prevent the fingers from being injured has been provided on a press but such an attachment is frequently complicated or requires springs to operate it or may limit the movement of the punch carrier or restrict the operation of the press.

One of the objects of this invention is to provide a safety attachment for use on a foot or power press which will be extremely simple in construction and yet will effectively protect the operator from getting a hand or finger caught between the punch and the die or die block that injury may occur.

Another object of this invention is to provide a safety attachment which will operate entirely by gravity and will need no springs or resilient material for effecting an efficient operation of the same.

Another object of this invention is to provide a safety attachment which is entirely supported by the punch carrier and which will not require the punch carrier to be limited in any of its movements, the safety attachment rather being of such an arrangement that the punch carrier may be lifted so as to entirely clear the attachment from the die and work and permit free manipulation of the work.

Another object of the invention is to provide a safety attachment which by reason of its arrangement need not be touched or in any way manipulated when the punch carrier descends upon the die after being lifted free from contact therewith.

With these and other objects in view, the invention consists of certain novel features of construction, as will be more fully described and particularly pointed out in the appended claims.

In the accompanying drawing:

Fig. 1 is a sectional view of fragmental portions of a press illustrating the punch and its carrier and my attachment in position thereon, the dotted lines indicating the lower position of the punch in engagement with the work and the relative position of the attachment with respect thereto;

Fig. 2 is a sectional view on substantially line 2—2 of Fig. 1;

Fig. 3 is a perspective view of the safety attachment;

Fig. 4 is a plan view of the main member of the safety attachment in blanked out form;

Fig. 5 is a perspective view of the member bent to shape;

Fig. 6 is a sectional view on substantially line 5—5 of Fig. 3; and

Fig. 7 is a sectional view on substantially line 6—6 of Fig. 3.

In proceeding with this invention I provide a guard which may conveniently be formed at the end of an arm and support the same in dependent relation on a pivot, the position of the arm being controlled by a stop so that when the arm descends to engage the die the angular relation of the arm will be such that the guard will be moved by the die in the desired direction across the path of the descending punch. The mounting of the arm will be such that gravity holds the same in position and no springs are required.

With reference to the drawing 10 designates the upwardly extending casting of a press from which an overarm extends for mounting the reciprocating head 11 in which the punch carrier 12 is secured by means of the set screw 13 engaging the stud 14 of the carrier. A punch 15 is mounted in this carrier 12 by means of the set screw 16 engaging the shank 17 thereof. The bed of the press 18 suitably mounts the die block 19 by means of the set screw 20. The work 21 is positioned on the die block in a location to be engaged by punch 15 as it descends.

The safety attachment consists essentially of a member designated generally 25 and shown in perspective at Fig. 4. A guard for swinging across the path of movement of the punch carrier and punch is conveniently formed integral with the member such for instance as by rolling the end of the sheet stock 26 as at 27. This portion 27 will be of a width desirable for sweeping across the work so as to remove any fingers which may be located at any point about the work and in the path of travel of the plunger or punch. In order to conveniently space this sweep arm or guard 27 above the work I provide flanges 28 on either end of this portion 27 (see Fig. 6). These flanges 28 are the heads of shank portions 29 extending into the hollow 30 of the roll 27 at the end of the member 25. These flanges 28 are of a distance apart to span the work and are in fixed relation with reference to the portion 27 but will be of a dimension to space it above the work as the portion 27 moves thereover.

The sheet stock 26 of the member designated generally 25 is slit as at 31 and 32, (see Fig. 3), to provide three arms 33, 34, and 35. The ends

of each of these arms are rolled to provide hinge eyes 36, while the arms 33 to 35 are bent at right angles to the sheet stock 26 (see Fig. 4) so as to provide offset arms. A cut-out portion 37 in the sheet stock 26 is formed through which the punch 15 may pass. The member 25, however, may comprise any connection between the hinge mounting and the guard such as merely an arm comprising the portion 38 at one side of this opening and which also will be at one side of the plunger.

This member 25 may be mounted directly upon the punch carrier in a pivotal manner through the hinge eyes 36 but a more convenient manner of handling the attachment so that it will be complete within itself is to provide a block or member 40 carrying a pivot pin 41 at its lower end 42 for the hinge eyes 36 of the arms 33 and 35 to engage as shown in Fig. 3. This block 40 also carries an abutment 42 which may be in the form of a threaded bolt having threads 43 to extend into the threaded opening 44 in this block 40. This abutment 42 is so positioned that it will be engaged by the rounded end 36 of the arm 34 forming a stop for locating the member 25 at the angle shown in Fig. 1. The block 40 may be secured to the carrier 12 in a suitable recess 47 by a bolt 45 passing through the opening 46 of this block to secure it in place. The edges of the recess prevents the block from rocking about the bolt 45.

The abutment 42 will be adjusted to engage the arm 34 so that the lower guard end 27 of the member 25 will always be positioned on the opposite side of a vertical passed through the pivot pin 41. A portion of the guard at the left of the pivot pin 41, illustrated in Fig. 1, is heavier than the portion of the guard at the right of the pivot pin thus always maintaining the guard and its lever arm 25 in substantially the angular position as shown in Fig. 1, even though this attachment is lifted clear of the die block 19, as shown in full lines in Fig. 1. An angularity, however, will be maintained such that when the carrier and the attachment descend so that flanges 28 of the guard engage the die block 19, the die will then sweep forwardly across the work 21, but out of contact therewith, into the dotted line position as shown in Fig. 1, so as to remove any person's fingers which might be in the path of travel of the punch.

By balancing the lever arm and guard, in the manner herein illustrated, no springs are required and the carrier may be lifted with its attachment clear of the work that the die may

be easily manipulated and no attention need be paid to the attachment when the carrier with its punch descends. There is no possibility of the attachment jamming because of the maintained angular relation.

The attachment complete as illustrated in Fig. 3 may be easily secured in place by a single bolt and all parts may be preadjusted if desired.

It will, of course, be apparent that as the guard is swept across the work the plunger will pass into the opening 37 in the sheet stock of the member 26 so as to engage the work.

I claim:

1. A safety attachment for a press having a reciprocating punch carrier and a die block comprising a member carrying a guard, means to pivotally support said member in a dependent relation on said punch carrier clear of the die block, and an adjustable stop to engage said member to position the same at such an angle to said die block that the guard will engage the die block and sweep across the path of movement of the punch carrier as the same descends.

2. A safety attachment for a press having a reciprocating punch carrier and a die block comprising a member having an offset arm and carrying a guard at one side of the arm, means to pivot said offset arm, a stop to engage the member on the side of the pivot distant from the guard, said guard being of a weight to gravitationally cause engagement with said stop, said guard being in a dependent relation from said pivot means at the other side of a vertical through said pivot from said stop.

3. A safety attachment for a press having a reciprocating punch carrier and a die block comprising a member having an offset arm and carrying a guard at one end portion of the arm, means to pivot said offset arm, a stop to engage the lever at the other end portion of said arm, said guard being of a weight to gravitationally cause engagement with said stop, said guard being in a dependent relation from said pivot means at the other side of a vertical through said pivot from said stop and at such an angle to said die block that the guard will engage the die block and swing about its pivot to sweep across the path of movement of the punch carrier as the same descends.

4. A safety attachment for a press as set forth in claim 1 wherein the guard has flanges thereon positioned at either side of the work to engage the die and space the guard from the work in its movement across the die.

JOSEPH E. SKOOG.
